COLLAPSIBLE BAG FRAME

William C. Hiering, Newark, N. J., assignor to
The J. E. Mergott Company, Newark, N. J., a
corporation of Delaware

Application June 22, 1935, Serial No. 27,838

2 Claims. (Cl. 150—45)

This invention relates to hand bags and more particularly to improvements in collapsible frames for hand bags.

Heretofore, there have been provided collapsible frames for hand bags, which frames when expanded present a substantially six-sided figure, and a wide opening to the hand bag, thereby enabling easy access to the contents therein. Such hand bags are generally known as "gate" bags. In the manufacture of hand bags of the "gate" type it is necessary that the bag covering material be properly attached to the bag frame; and during the attaching process the frame is subjected to strains which heretofore in many instances have distorted the frame to such an extent that it will not function properly during the opening or closing of the hand bag. The present tendency in the manufacture of hand bags is to use a frame having as little metal as possible. Such frames are preferably of a channel type; and in such shapes it is necessary that the various parts of the frame be joined together in such a manner as to provide the proper rigidity and positiveness of operation at all times.

It is therefore, an object of this invention to provide a frame of the collapsible type for hand bags, which frame has the various elements thereof hingedly connected together in such a manner as to avoid the possibility of distortion during the attaching of bag covering material to the frame or during the general use of the hand bag, and to provide the proper rigidity when the frame is extended or collapsed.

A further object is the provision of a collapsible frame which enables a wide opening in the hand bag without distorting the hand bag or affecting the shape thereof in any manner.

These and other advantageous objects, which will later appear, are accomplished by the simple and practical construction and arrangement of parts hereinafter described and exhibited in the accompanying drawing, forming part hereof, and in which:

Fig. 1 is a plan view of a hand bag frame of the collapsible type in an expanded condition,

Fig. 2 is a plan view of a hand bag frame in a collapsed condition,

Fig. 3 is a perspective view partially in section showing details of a hinge connection between members of the frame,

Fig. 4 is a plan view of a hinge connection between members of the frame, and

Fig. 5 is an elevational view showing the hinge connection applied to a modified form of the frame member.

Referring to the drawing, the frame is shown to comprise longitudinal members 11 and 12, and end members 13, 14 and 15 and 16. The members 13 and 14 are pivotally connected at 17 and in turn hingedly connected to longitudinal members 11 and 12. Similarly members 15 and 16 are pivotally connected at 18 and respectively hingedly connected to members 11 and 12. It will be seen that the frame is capable of being collapsed so that members 13 and 14, 10 and 11 and 12, and 15 and 16, will be parallel to and abut each other as shown in Fig. 2.

Each of the members preferably has an inner side wall 19 provided with an outwardly directed right angled flange 20, the latter being provided with a downturned portion 21 spaced from and parallel to the side wall 19. The lower edge of wall 19 is provided with spaced tabs 22 having perforations 23 to facilitate the upward bending of the tabs for the purpose of clamping an inlay 20 49 to the frame member, said inlay having bag covering material 41 attached thereto, see Fig. 3.

At the junction of member 13 and member 11 the flange 20 on member 11 is extended to provide a lip 28, and the side wall 19 is cut and looped to form a bearing 24 through which passes a pin 25, the latter passing also through a similar bearing 26 formed by bending a portion of the side wall 19 of member 13. The flange 20 of member 13 at the extremity thereof has the downturned portion 21 omitted, and the flange is depressed providing a lip 27 positioned below the lip 28 formed from the flange on the member 11 as above described.

The lip 27 has the outer edge thereof rounded as shown at 29 and the inner side thereof flat as shown at 30 to abut against the side wall 19 of member 11 when the members 11 and 13 are in alignment. The lip 27, by means of its side 40 30 abutting the side wall 19 of member 11, prevents any movement of the members beyond a position of alignment when the frame is in a collapsed position.

When the frame is expanded, the adjacent 45 ends of members 13 and 11 will abut each other and thereby limit the movement of said members in the expanding direction.

The hinge connection between members 13 and 11 as above described is also employed between members 15 and 11 and members 14 and 16 and 12.

Members 15 and 16 and members 13 and 14 are hingedly connected by means of rivets 31; but no means are provided at the junctions 17 and 55

18 for limiting the movement of said members in any direction, the limiting means being confined to the hinge connections as above described between members 13 and 11, and 15 and between members 14, 12 and 16.

In Fig. 5 there is shown a fragment of a frame, the members of which have a side wall 42 with an outwardly directed right angled flange 43. The lower end of the side wall has integral therewith and extending substantially the length thereof, a flange 44, which is bendable upwardly into a position substantially parallel with the side wall 42, for the purpose of clamping an inlay carrying bag covering material to the frame member. The hinge connection between adjacent members in this type of frame is substantially the same as has been described above in connection with Figs. 1, 2 and 3.

It will be seen that when in the expanded condition, the frame will assume a definite shape and distortion thereof is prevented due to the limiting means at the hinge connections between the various members. Similarly, when the bag is collapsed, one-half of the members will be in alignment and parallel to the other half of the members which will be in alignment; and movement of the various members beyond the position of alignment is prevented as above described.

From the above description it will be seen that there has been provided a frame which is rigid in construction and capable of withstanding the severe distortional stresses and strains to which frames of the collapsible type are subjected during the general use of a hand bag and during the attaching of bag covering material to a hand bag frame.

The foregoing disclosure is to be regarded as descriptive and illustrative only, and not as restrictive or limitative of the invention, of which

obviously an embodiment may be constructed including many modifications, without departing from the general scope herein indicated and denoted in the appended claims.

Having thus described my invention, what I claim as new and desire to secure by Letters Patent, is:

1. In a hand bag frame of the collapsible type, a pair of members hingedly connected to each other, each of said members having a side wall 10 with an outwardly directed flange at the upper edge thereof, the flanges at the extremities of adjacent ends of said members being formed into lips resting one above the other, the lowermost lip having an edge shaped to engage a side wall of the other member when said members are in alignment and limit the movement thereof, the extremities of said side walls being formed into tubular bearings, and a hinge pin 15 passing through said lip and through said bearing.

2. In a hand bag frame of the collapsible type, a pair of frame members hingedly connected to each other, each of said members having a side wall with an outwardly directed flange, said 25 flange being provided with a downturned portion parallel to the side wall, the flanges of said member adjacent the hinge connection being extended to form lips and the extremities of the side walls being bent to provide tubular 30 bearings, a hinge pin passing through said lips and bearing, the lip on one of said members being positioned below the lip on the other member and having an edge thereof shaped to engage the side wall of the other members when 35 said members are in alignment to limit the movement of said members, the downturned portion of said flange being cut away adjacent the hinge connection.

WILLIAM C. HIERING. 40
